UNITED STATES PATENT OFFICE.

JOHN M. MCINTYRE AND ROBERT MEGINNITY, OF DETROIT, MICHIGAN.

IMPROVED WATER-HEATER.

Specification forming part of Letters Patent No. 44,542, dated October 4, 1864.

To all whom it may concern:

Be it known that we, JOHN M. MCINTYRE and ROBERT MEGINNITY, of Detroit, in the county of Wayne and State of Michigan, have invented a new and Improved Water-Heater for Stoves and Ranges; and we do hereby declare that the following is a full, clear, and exact description thereof, which will enable those skilled in the art to make and use the same, reference being had to the accompanying drawings, forming part of this specification, in which—

Figure 1 is a vertical central section of our invention, taken in the line xx , Fig. 2; Fig. 2, a horizontal section of the same, taken in the line $x'x'$, Fig. 1.

Similar letters of reference indicate corresponding parts.

This invention has for its object the dispensing with the ordinary "water-back," which are placed in stoves and ranges and communicate by means of pipes with the heater or water-receptacle in order to heat the water therein. These water-backs absorb a great amount of heat and greatly deteriorate the baking qualities of the stove.

Our invention consists in substituting for the water-back within the stove or range a coil-pipe placed in the stove pipe or flue or over a hole in the top of the stove or range, said pipe communicating with the heater, and all arranged in such a manner that the water will be heated from the waste heat that passes into the pipe or flue, thereby not interfering in the least with the cooking qualities of the stove or range.

A represents a copper heater, which may be constructed in the usual way and therefore does not require any special description.

B represents a coil-pipe constructed of copper and having its ends connected with pipes C C', which communicate with the heater A, one above the other, as shown clearly in Fig. 1. The coil-pipe B is placed within the pipe or flue of the stove or range, so that the products of combustion may pass through and around it and heat the water therein, a circulation being thereby formed through the coil B and heater A. By this arrangement the fire in the stove or range is not deprived of any of its heat to warm the water in A, as the coil B is heated by the waste heat which passes into the pipe or flue.

In carrying out this invention it is not strictly essential that the coil B be placed in the pipe or flue. It may in certain cases be placed over a hole in the top plate of the stove or range, or in a place where an ordinary boiler is fitted. The coil B may be arranged in various ways. In the drawings it is represented as being around a cone, D, which is placed within a cone, E, the heat passing up through the latter. Other plans, however, may be devised to effect the same end.

We claim as new and desire to secure by Letters Patent—

A coil-pipe, B, combined and arranged with a water-heater, A, in such a manner that the coil may be heated by the waste heat, either within the pipe or flue of the stove or over or on the latter, or at any point or place outside the fire-chamber of the stove or range, substantially as and for the purpose set forth.

JOHN M. MCINTYRE.
ROBERT MEGINNITY.
